SAND GLASS TIMER

Robert W. Young, Des Moines, Iowa

Application August 1, 1956, Serial No. 42,484

Term of patent 14 years

(Cl. D42—7)

FIG. 1

FIG. 2

FIG. 3

Fig. 1 is a front elevational view of a sand glass timer, showing my new design;

Fig. 2 is a side elevational view;

Fig. 3 is a top plan view thereof.

I claim:

The ornamental design for a sand glass timer, substantially as shown.
